UNITED STATES PATENT OFFICE.

FREDERICK A. BROOKS, OF URBANA, ILLINOIS.

ROTARY ENGINE.

1,226,745.

Specification of Letters Patent. Patented May 22, 1917.

Application filed October 19, 1914. Serial No. 867,321.

To all whom it may concern:

Be it known that I, FREDERICK A. BROOKS, a citizen of the United States, residing at Urbana, in the county of Champaign and 5 State of Illinois, have invented certain new and useful Improvements in Rotary Engines, of which the following is a specification.

My invention relates to improved rotary 10 constructions susceptible of employment as engines or motors either of the internal combustion or steam type, and also capable of use as air compressors, clutches, brakes, water or other liquid motors, pumps, and the 15 like.

One of the objects of this invention is the production of a simple structure of this 20 general character which will be economical to manufacture and operate and will be composed of few parts of simple design capable of easy assemblage. In the improved embodiments of the invention all of the moving parts are supported in suitable bearings 25 easily accessible for inspection and attention, and it is preferred to combine the rotor of the mechanism with coöperating rotary valves, whereby in the strictest sense the 30 construction is a true rotary machine.

When the invention is incorporated in an 35 internal combustion or explosion rotary engine, the gaseous mixture is compressed by a part of the rotary member while ahead of the same and then by suitable mechanism is transferred or shifted behind it and there 40 ignited or exploded to produce the rotation desired. Another feature of the invention when embodied in a gas-engine is the transfer of the compressed gaseous mixture to the chamber from the side or sides of the 45 controlling valves. These, with other features of novelty and improvement will become apparent to those skilled in the art from a consideration of the construction and operation of preferred embodiments of 50 the invention as applied to rotary gas-engines, described below and illustrated in the accompanying drawings forming a part of this patent application. In these drawings like parts are supplied with the same reference characters throughout.

In the drawings:

Figure 1 is a vertical section through a 55 rotary gas or internal combustion engine, incorporating therein certain features of this invention;

Fig. 2 is a horizontal section on line 2—2

of Fig. 1, the parts being viewed in the direction indicated by the arrows;

Fig. 3 is a vertical section through a modified form of engine construction with a 60 different means for igniting the charges, and

Fig. 4 is a section on line 4—4 of Fig. 3 with the rotor in a slightly different angular position.

Referring first to Fig. 1, which illustrates a triple or three channel design of rotary engine of the internal combustion type, it will be observed that the construction has a stationary, substantially cylindrical casing 70 composed of two matching or registering parts 11 and 12, each with outstanding flanges 13, 13, fastened together by securing screws or bolts 14, 14. At its opposite sides this divisible casing or shell is equipped 75 with two bearings 15 and 16 in which is revolvably mounted a shaft 17 having keyed or otherwise fastened thereto a hollow drum or rotor 18, snugly fitting the interior of the casing and supplied on its cylindrical periphery with three parallel annular grooves, channels, or compartments 19, 20, and 21, each of which is divided into a pair of chambers 22 and 23 by partition or division walls 24 and 25 shaped in cross-section somewhat like gear teeth and having their outer faces flush with the cylindrical surface of the drum or rotor. In the preferred embodiment illustrated in Fig. 1, these partition or division-walls are disposed diametrically 80 opposite one another.

The surrounding casing or shell 10 opposite each of these annular compartments is supplied with an inlet opening or passage 26 for the admission of the explosive gases, an 95 exhaust or outlet opening or passage 27, and an ignition spark-plug 28, all properly positioned with reference to one another to efficiently perform their functions, the angular positions of these three serving the three 100 compartments being substantially the same so that the rotary-valves hereinafter referred to may be mounted on the same shafts.

The two half-shells 11 and 12 are shaped at 29 and 30 adjacent to the exhaust and inlet ports so as to provide interiorly of the casing a smaller cylindrical cavity intersecting the main large cavity of the shell. This smaller recess or cavity accommodates three rotary valves 36, 31, and 37, mounted 110 on a shaft 32 revolvble in the divided bearings 33 and 34 forming parts of the casing.

As is shown in Fig. 1, the middle rotary valve 31, which for convenience of description may be characterized an inlet valve, is recessed or cutaway across its face at 35 for the temporary accommodation individually of the walls 24 and 25, the recess and either wall being adapted in their rotary movements to intermesh or interfit, as is clearly illustrated. Valve 31 is of substantially the same width as its corresponding annular channel or compartment of the rotor 18 and is adapted to extend to the bottom of such compartment acting as a rotary or movable partition or division wall for the compartment. Each wall 24 and 25 of the three compartments 19, 20, and 21, is displaced angularly 120° with reference to the corresponding walls of the three adjacent compartments so that the action of the engine will correspond to that of a three cylinder engine. The cavities or recesses of the three valves 36, 31, and 37, are also angularly displaced 120° from one another to correspond to the different positions of the walls 24 and 25.

The casing or shell-members 11 and 12 are so shaped at 38 and 39 as to provide another internal cylindrical cavity intersecting the main cavity accommodating the rotor. The part 12, however, of the casing, is so shaped or formed as to provide a compression chamber 40, the function of which is described below.

On a shaft 41, rotatable in bearings 42, 43, of the shell-member 12, three compression rotary valves 44, 45, and 46 are keyed or pinned, each of such valves being of the same width as its corresponding compartment in the rotor and extending to the bottom thereof, as is shown, and each of these valves has a peripheral cavity or recess 47 adapted to accommodate the walls 24 and 25 as they pass by, the three cavities being 120° apart. At one end each of the shafts 41, 45, 17 and 32, has fastened thereto the collars 48, 49, and 50 and the opposite end of the shaft 17 has fixed thereto the gear 51 which at its opposite sides meshes with the teeth of gears 52 and 53 mounted on shafts 32 and 41 respectively. In this way the rotation of the shaft 17 is transmitted to the two sets of rotary valves, inlet and compression, each set of valves making two revolutions to one revolution of the rotor or drum.

Operation: The operation of this appliance when employed as a gas or internal combustion engine is substantially as follows, and, since the operations of its three parts or sections are practically alike, a description of the functions of the elements of one rotor channel section will suffice.

When one of the walls, 25 for example, in its rotation reaches the position of the valve 31, the recess 35 of the latter being so shaped and positioned as to receive the wall

and move with it, the two parts intermesh, as illustrated in Fig. 1, and when thus interfitted, form a substantially fluid-tight joint. The rotation of the valve 31 is provided for the purpose of permitting the wall 25 to pass by, the two parts 25 and 31 both constituting partition or division walls, the movements of which would conflict if provisions were not made for their intermeshing or passage by one another, as shown. When the wall 25 leaves the recess of the valve 31, the latter extends to the bottom of the groove 20, dividing it into two chambers and forming the rear wall of an increasing arcuate chamber of which the partition wall 25 forms an advancing front-wall.

After the wall 25, which in effect corresponds to the plunger or piston of a cylinder engine, passes the inlet 26, its continued forward movement causes a suction which draws in behind it a charge of mixed air and gas through the intake port. This continues until the part 25 enters the recess of the rotary valve 45 and as the division-wall 25 passes beyond the valve 45, the latter by extending to the bottom of the groove closes the front end of this arcuate chamber. By this time, the wall 24 will be passing by and intermeshing with the valve 31, and as it advances beyond the intake port, it compresses the charge previously drawn in by the part 25, it being readily understood that the rotary travel of the rotor and the wall 24 decreases the size of the chamber, owing to the relatively stationary position of valve 45.

It should be observed that whenever any portion of the cavity 47 of the valve 45 extends outwardly beyond the periphery of the rotor, it is in communication sidewise as axially of the valve with the compression chamber 40, which is in association with all three of the valves. This axial communication is shown with reference to valve 45 in Fig. 2. It will be apparent, therefore, that near the end of the compression movement of the part 24, the valve 45, in turning to receive it in its cavity, will establish communication between the rotor groove and the pressure chamber 40 so that the charge compressed by the wall 24 will be delivered into the chamber 40. The wall 24 passes into and out of the recess 47 of the rotating valve and, as it is leaving such recess, as shown in Fig. 1, the valve establishes communication between the chamber 40 and the portion of the rotor channel chamber at the rear of the division-wall 24, so that a supply of the compressed mixture is delivered back of or to the rear of the advancing wall 24. That is to say, the valve 45 acts as a transfer medium to shift the compressed charge from in front of the wall 24 to the rear thereof. As the wall 24 advances, the valve 45 closes the rotor groove and breaks

its connection with chamber 40 and when the wall has passed the ignition device or spark plug 28 the latter ignites the charge, exploding the same in the usual manner, 5 the mixture expanding in the customary way and acting on the rear face of the wall 24, causing the rotor to be revolved, the rear wall of the explosion compartment being formed by the relatively-stationary valve 45. The travel of the wall 24, as will be 10 readily understood, acts to discharge ahead of it through the exhaust-port 27 the exploded gases which had previously acted against the wall 25. In this way, each of 15 the two walls 24 and 25 acts to suck in the charge for the other and to expel the exploded gases of the other, but each wall has exploded behind it the charge which it had previously compressed ahead of it, and 20 which was transferred back of or around it by the valve 45. This action applies particularly to an engine with entirely independent grooves or channels, but is somewhat modified when a single compression 25 chamber is associated with a plurality of such channels.

Although the compression and explosion-expansion movements of the rotor are not equal, the valves 31 and 35 not being diametrically opposite one another, it may be 30 stated, however, in a general way, that the charge is drawn in by one division wall during one-half revolution of the rotor, is compressed by the second wall during the next 35 half revolution, is exploded and expanded behind the second wall during the succeeding half revolution, and is expelled by the first wall during the next half revolution period of the rotor. But neither of 40 these walls is ever idle, and if they are thought of as corresponding to the pistons of a reciprocating engine, this rotary engine may be considered as double-acting, with compression in front of each wall and 45 explosion and expansion behind it. Stated differently, when one wall is compressing a charge ahead of it and drawing in a new charge behind it, the other wall is having its charge behind it exploded and expanded 50 while the preceding exhausted charge ahead of it is being expelled through the discharge port. In other words, suction, compression, expansion, and expulsion are all occurring at substantially the same time. 55 Thus, two cycles are started per revolution as distinguished from one cycle per other revolution of the four-stroke cycle, single-acting, reciprocating gas-engine.

In the device illustrated, a plurality of 60 angular compartments or channels corresponding to a plurality of cylinders in a reciprocating engine are shown, the occurrences taking place in the various compartments being alike, except that they are offset with respect to the time of their happen-

ing, so as to produce in the rotor a more uniform torque. The number of rotor channels and the number of chambers into which they may be divided is, of course, capable of a wide range, without departure from the invention. By employing a common compression chamber into which all of the compressed charges are temporarily stored, the pressure therein may be maintained more uniform than would be possible if each annular compartment had its own individual compression chamber. 70

It should be observed furthermore, that in a construction of this kind the intake chamber and the explosion-expansion chamber need not necessarily be of the same volume, as is substantially inherently necessary in the usual reciprocating gas-engine. Consequently, in this structure it is desirable to make the explosion and expansion chamber 80 somewhat larger than the intake chamber to secure a higher degree of efficiency by obtaining a greater degree of expansion of the gases. 85

In Figs. 3 and 4 a somewhat modified 90 construction is illustrated, which differs from the embodiments shown in Figs. 1 and 2 only in that the number of rotor compartments shown is two instead of three, and, also, in the ignition appliance which does 95 away with the spark plug, except for the preliminary starting of the engine. Inasmuch as the construction of many of the parts is the same as set forth above, they are given the same reference characters. In 100 this instance, however, the heated exploded gases from the one compartment are employed to fire the charge in the companion compartment and the gases in the latter in turn ignite the charge in the first compartment, and so on. 105

In this case, the upper half of the casing 60 is enlarged at 61, at which point it is provided with a small transverse ignition chamber 62 having a central passage 63 and 110 two side passages 64 and 65 opening into the interior of the casing. Opposite each of the annular rotor compartments the inner face of the casing is equipped with four passages 66, 67, 68, and 69, each extending from 115 a point opposite the corresponding rotor compartment to a point at one side of the compartment. The rotor or internal drum, which in this instance is equipped with two grooves 70 and 71, is cored out at 72 and 73 120 so that the cavities will register with the ends of the ports or openings 65 and 69 and 63 and 68 respectively, whereby, when the compressed mixture in the groove 70 is ready to be fired or ignited these cavities 125 72 and 73 will come into register with the passages 65, 69, 63, and 68, putting the groove 70 into communication with the chamber 62 from both sides so that the hot gases in the chamber may explode the compressed mixture in 130

the groove and at the same time trap a portion of such hot exploded gases.

The rotor also has similar cavities or recesses 74, 75, just to the rear of the division-wall 25, which, at the proper time, will register with the openings 63, 67, 64, and 66, establishing communication between the groove 71 and the chamber 62, whereby the compressed gases in the groove will be exploded and a portion of the gases trapped in the compartment 65. In this way each groove receives its ignition from this chamber of the outer casing and in turn delivers hot gases thereto for the firing of the mixture or charge in the companion groove. Otherwise, the construction, being like that described above, requires no further elucidation.

To those skilled in this art, it will be apparent that many mechanical changes may be incorporated in these embodiments of this invention without departure from the heart and essence of the latter and without the sacrifice of any of its substantial benefits and advantages, and for that reason, these incorporations of the invention should be taken only as a few of several ways of embodying the invention in practical form.

It will be apparent that in many instances the construction and functions of the various parts of the mechanism may be reversed without modification of the principle of operation.

I have defined the scope of the invention by the appended claims and have, therefore, refrained from setting forth various other embodiments of the invention, since the principal feature of the same can be readily understood from the two structures herein detailed.

I claim:

1. In a rotary engine construction of the character described, with suitable intake, exhaust, and ignition, the combination of a casing provided with a compression chamber, a rotor revolvable in said casing and having an annular compartment facing the casing, a partition wall on said rotor dividing the compartment into chambers, a valve in said casing coöperating with the rotor compartment to cause the compression of the gas charge ahead of said compression wall, deliver it axially of the valve into the compression chamber, and transfer a charge axially of the valve from said compression chamber to the rear of the partition wall for ignition and explosion, substantially as described.

2. In a rotary engine construction of the character described, with suitable intake, exhaust, and ignition, the combination of a casing provided with a compression chamber, a rotor revolvable in said casing and having a compartment facing the casing and a partition wall dividing the compartment

into chambers, a recessed rotary valve in said casing projecting into the compartment and dividing the same into chambers and adapted to establish and break sidewise communication between the compartment and said compression chamber and adapted by the entering of the partition wall into its recess to permit the passage of said wall past the valve, and means to rotate said valve whereby to cause the compression of a gas charge ahead of said partition-wall, deliver such charge axially of the valve into the compression chamber, and discharge a charge axially of the valve from said compression chamber to the rear of said partition wall for ignition and explosion, substantially as described.

3. In a rotary engine construction of the character described, the combination of a casing provided with suitable intake-port, exhaust-port, ignition and a compression chamber, a rotor revolvable in said casing and having a compartment facing said casing divided by partition walls into chambers, a valve in said casing between the intake and exhaust ports and projecting into said compartment, dividing it into chambers, a second valve in said casing projecting into said compartment and dividing it into chambers, and adapted to establish and break communication axially of the valve between said rotor compartment and compression chamber, and means to operate said valves to permit the passage of the partition walls past the same, whereby a charge of gas is drawn in behind one of said walls, is compressed between another of said walls and said second valve, is delivered by said second valve axially of the valve into the compression chamber, and a charge from the latter is delivered by said second valve axially thereof to the rear of said wall for ignition and explosion, substantially as described.

4. In a rotary engine construction of the character described, the combination of a casing provided with suitable intake-port, exhaust-port, ignition, and a compression chamber, a rotor revolvable in said casing and having a compartment facing said casing divided by partition-walls into chambers, a recessed rotary valve in said casing between the intake and exhaust ports and projecting into said compartment dividing it into chambers, a second recessed rotary valve in said casing projecting into said compartment and dividing it into chambers, and constructed to establish and break communication axially of the valve between said rotor compartment and compression chamber, the recesses of said valves being adapted to temporarily accommodate said partition walls and permit their passage past the valves, and means to revolve said valves, whereby a charge of gas is drawn

in behind one of said walls, is compressed between another of said walls and said second valve, is delivered by said second valve axially thereof into the compression chamber, and a charge from the latter is delivered by said second valve axially thereof to the rear of said wall for ignition and explosion, substantially as described.

5. In a rotary engine construction of the character described, the combination of a casing provided with suitable intake-ports, exhaust-ports, ignition, and a compression chamber, a rotor revoluble in said casing and having a plurality of compartments facing said casing, each compartment being divided by partition walls into chambers, a recessed rotary valve in said casing for each of the rotor compartments between the corresponding intake and exhaust ports and projecting into the compartment, dividing it into chambers, and adapted to establish and break communication between the corresponding rotor compartment and said compression chamber, the recesses of said valves being adapted to temporarily accommodate said partition walls and permit their passage past the valves, and means to rotate said valves, whereby a charge of gas is drawn in behind one of the partition walls of each compartment, is compressed between another of the partition walls of said compartment and the corresponding second valve, is delivered by said second valve axially thereof into the compression chamber and a charge from the latter is delivered by said second valve to the compartment rearwardly of said wall for ignition and explosion, substantially as described.

6. In a rotary engine construction of the character described, the combination of a casing provided with suitable intake-ports, exhaust-ports, ignition, and a common compression chamber, a rotor revoluble in said casing and having a plurality of compartments facing the casing divided by partition walls into chambers, the partitions of the various compartments being angularly offset, a recessed rotary valve in said casing for each of said compartments between the corresponding intake and exhaust ports and projecting into the compartment dividing it into chambers, a second recessed rotary valve in said casing for each of said compartments projecting into its compartment and dividing it into chambers and adapted to establish and break communication between said rotor compartment and said common compression chamber, the recesses of said valves being adapted to temporarily accommodate said partition walls and permit their passage past the valves, and means to revolve said valves, all of said first-mentioned valves being on a single shaft and all of said second valves being on a single shaft, the recesses of said valves being angularly

offset to correspond to the angular disposition of said partition walls, substantially as described.

7. In a rotary construction of the character described, the combination of a chambered casing, a rotor revoluble in said casing and having a compartment, a valve in said casing projecting into said rotor compartment and constructed to establish and break communication between said chamber and compartment axially of the valve, and means to operate said valve, substantially as described.

8. In a rotary construction of the character described, the combination of a chambered casing, a rotor revoluble in said casing having an annular compartment, a recessed rotary valve in said casing projecting into said compartment and adapted to establish and break communication between said compartment and casing chamber axially of the valve, and means to operate said valve, substantially as described.

9. In a rotary engine of the character described, the combination of a casing provided with suitable intake-ports, exhaust-ports, ignition, and a common compression chamber, a rotor revoluble in said casing and having a plurality of compartments facing said casing, each of said compartments being divided by a partition wall into chambers, and a valve in said casing for and projecting into each of said compartments dividing it into chambers and constructed to establish and break communication between said compartment and common compression chamber, said valves and partition walls being constructed to permit their passage past one another, substantially as described.

10. In a rotary-engine construction of the character described, the combination of a casing provided with suitable intake-ports, exhaust-ports, ignition, and a common compression chamber, a rotor revoluble in said casing and having a plurality of compartments facing said casing, each divided by a partition wall into chambers, a recessed rotary valve in said casing for and projecting into each of said compartments dividing it into chambers, said valves being constructed to establish and break communication between said rotor compartments and the common compression chamber, the recesses of said valves being adapted to temporarily accommodate said partition walls and permit their passage past the valves, and means to revolve said valves, substantially as described.

11. In a rotary engine construction of the character described, the combination of a casing provided with suitable intake-ports, exhaust-ports, ignition, and a common compression chamber, a rotor revoluble in said casing having a plurality of annular compartments facing said casing, each of said

compartments being divided by one or more partition walls into chambers, a valve in said casing between the intake and exhaust ports for each of said compartments, each 5 of said valves projecting into the corresponding compartment and dividing it into chambers, a second valve in said casing for and projecting into each of said compartments dividing it into chambers and constructed to establish and break communication between the compartments and common 10 compression chamber, said valves being constructed to permit the passage of the partition walls past them, and means to operate 15 said valves, substantially as described.

12. In a rotary construction of the character described, the combination of a cham-

bered casing, a rotor revoluble in said casing having a plurality of annular compartments, a recessed rotary valve in said casing for and projecting into each of said compartments and adapted to establish and break communication between said compartments and said casing chamber axially of the valves, and means to operate said valves, substantially as described. 20 25

In testimony whereof I have hereunto signed my name in the presence of two subscribing witnesses.

FREDERICK A. BROOKS.
